[57] CLAIM

The ornamental design for a combined scissors and angled-blade comb, as shown and described.

DESCRIPTION

FIG. 1 is a front elevational view of a combined scissors and angled-blade comb showing my new design;

FIG. 2 is a rear elevational view thereof;

FIG. 3 is a left end elevational view thereof;

FIG. 4 is a right end elevational view thereof;

FIG. 5 is a top plan view thereof;

FIG. 6 is a bottom plan view thereof; and

FIG. 7 is a reduced perspective view thereof.

The broken lines representing the human form are shown for illustrative purposes only.
